PISTON RING COMPRESSOR

Joseph Sunnen, Kirkwood, Mo.

Application June 4, 1934, Serial No. 728,933

5 Claims. (Cl. 29—86.4)

My invention has relation to improvements in piston ring compressors and it consists in the novel features of construction more fully set forth in the specification and pointed out in the 5 claims.

The object of the invention is to provide a compressor which may be applied to a piston over the piston ring for compressing said rings into their grooves to enable the piston together with the 10 rings to be readily inserted into an engine cylinder. A further object is to provide a compressor in the general form of a band that when applied will not assume a cone shape and thus allow the rings to expand out of their grooves.

A still further object of the invention is to provide a ring compressor that is simple and easy of application. It is also an object of the invention to form the compressor in such a manner that it is readily adaptable to different sizes of 15 pistons and will compress the rings of a large piston and the rings of a small piston with equal facility.

The manner of accomplishing these objects, as well as other advantages inherent in the invention, will be better apparent from a detailed description of the same in connection with the accompanying drawings, in which:

Figure 1 is a side elevation of a piston, the rings of which are held in compression by my improved 30 compressor which has just been applied, the applicator therefore being still in place; Fig. 2 is a longitudinal section through the compressor and applicator, the piston being shown in cross-section, the combined section being indicated by 35 the line 2—2 of Fig. 1; Fig. 3 is a side elevation of a piston with the compressor applied thereto and the applicator removed; Fig. 4 is a plan view of the applicator with the parts in position for engagement with the ring compressor for the purpose 40 of applying the same to a piston; Fig. 5 is a bottom plan of the applicator with the parts in the same relative positions as shown in Fig. 4; Fig. 6 is a top plan of a piston with my improved ring compressor applied thereto; Fig. 7 is a side elevation of a piston with the ring compressor applied turned through an angle at 45 90 degrees from the side elevation shown in Fig. 3; Fig. 8 is a perspective view of the ring compressor with the ends of the band disconnected and spread apart for the purpose of showing the construction to a better advantage; Fig. 9 is an end view of a piston showing a modified form of ring compressor applied thereto; Fig. 10 is a side elevation of a piston and said modified form 50 of compressor thereon looking toward the 55

wedge-plate that serves to contract the compressor band and hold the same in place; Fig. 11 is a side elevation of a piston and the modified form of compressor looking at an angle of 90 degrees to the elevation shown in Fig. 10; Fig. 12 is a cross-sectional detail through the wedge-plate taken on the line 12—12 of Fig. 10; and Fig. 13 is a perspective view of said wedge-plate.

Referring to the drawings, P represents an engine piston, the rings r of which are being held compressed within the ring grooves by means of my improved ring compressor C which has just been applied thereto by means of a special tool which I choose to call an applicator A, which tool is removed, of course, before the piston is inserted into the engine cylinder, to be more fully described hereinafter. My improved ring compressor will probably be more easily understood if I describe the compressor and the applicator separately.

The ring compressor C comprises a metallic band 1 bent into a general circular shape, one end of which has on its lower edge (with reference to the position of the band on the piston) a laterally projecting lug 2. A short distance removed from the lug 2 two ridges 3, 3' are formed in the band in spaced relation, the formation of which provides channels 4, 4' on the inside of the band. The upper part of the ridge 3' is cut away to provide a clearance for the applicator (as we shall see hereafter) which leaves a notch n in the band above the ridge 3'. A short stud 5 is passed through an opening in the middle of ridge 3', the rectangular head 6 of which nests within the channel 4' and the outer end 5' of which is riveted over to prevent the removal of nut 7, but allowing said nut sufficient movement so that it may be loosened. The upper edge of band 1 is crimped outwardly at two points 8, 8' in spaced relation, said crimps being so located that they will come opposite to the overlapping ends of the band when it is in place on a piston (Fig. 6).

The upper end 9 of the band 1 is reduced in width and has a slot 10 formed in it, which slot terminates at its outer extremity in an enlarged portion 10' for the purpose of receiving the nut 7 when the ends of the band are brought together in operative relation, during which it is necessary to slide the stud 5 through the slot 10 in tightening the band about the piston rings r, r.

The application tool for the ring compressor, which I have termed an applicator A, comprises a base plate 12 relatively stationary and a draft member comprising a plate 13. The base plate 12 has a longitudinal slot 14, and the draft mem-

ber 13 has a confining plate 15 and a draft plate 16 secured in spaced relation by a post 17 and shouldered sleeve 18 mounted thereon. The confining plate 15 lies flat against one side of the 5 base plate 12 and has a recess 19 at one end, on each side of which are confining fingers 20, 20 bent slightly away from the base plate 12. Between the confining fingers 20, 20 is a tongue 21 bent inwardly so as to enter the slot 14 in the 10 base plate 12. The draft plate 16 is held in spaced relation with the confining plate 15 by a washer 22 mounted on the shouldered portion 23 of sleeve 18 and bearing against the base plate 12, and a spring washer 24 bearing against the draft 15 plate 16 and head 18' of the sleeve 18. The shouldered portion 23 of the sleeve 18 traverses the slot 14 in the base plate 12. A set screw 25 and washer 26 hold the sleeve on the post 17. One end of the draft plate 16 is provided with 20 a finger 27 adapted to operate in the slot 14 of the base plate, and the other end of the base plate is bent outwardly to provide a finger piece 28 against which pressure may be exerted in order to rock the said draft plate and depress the finger 27, as will more fully hereinafter appear.

The post 17 has a head 29 which bears against the confining plate 15, which head is provided with a tapped opening 30 for the threaded shank 31 of an adjusting handle 32. The base plate 12 30 has an extension 33 at the end that engages the ring compressor and a flange 34 at the other end. There is a tapped boss 35 on the flange 34 through which the threaded shank 31 passes. It will be observed that there are two threads 35 of opposite hand on the shank, one passing through the boss 34 on the relatively fixed base plate 13 and the other passing through the head 29 of post 17 on the movable draft member 13.

In the operation of my improved ring compressor the ends of the band are adjusted so that the stud 5 is just at the outer end of the slot 10 whereupon the applicator A is brought into engagement with the band. This is done by 40 tilting the draft plate 16 so as to depress the finger 27 until it lies in a plane below the inner surface of the base plate 12. The end 9 of the band may now be slipped into the space between the base plate and confining fingers 20, 20 of the confining plate 15 and the draft plate released so that the finger 27 will enter the 45 enlargement 10' of slot 10. If the operator now rotates the handle 32 the screw shank 31 will cause the base plate 12 and draft member 13 to be relatively moved so that the ends of the confining fingers 20, 20 and the draft finger 27 will 50 separate. In this separation the ends 12', 12' of base plate 12 will bear against ridge 3' and the draft finger 27 will pull on the end 9 of the band 1, thus contracting the band and compressing 55 the piston rings confined by the band. When the piston rings have been compressed entirely within their grooves the nut 7 is tightened so as to hold the band securely in its compressed condition, whereupon the applicator may be released by rotating the handle 32 in the opposite 60 direction to remove the tension from the parts of the applicator and then rocking the draft plate so as to release the draft finger 27 from the end 9 of the band 1. It is, of course, essential 65 that the crimped portions 8, 8' of the band be at the top of the piston so that when the piston is pushed through the band into the cylinder these crimped portions will bear against the face of the cylinder block making it impossible for the band 70 75 1 to enter the cylinder. During the contraction

of the band upon the piston rings it is impossible for the band to spread outwardly at its upper edge into a cone shape because the ends of the band are confined against axial movement by the lug 2 and the slot 10.

In the modification shown in Figs. 9 to 13, inclusive, the ring compressor comprises a band 50, the ends 51, 52 of which are adapted to be overlapped to form the band in a general circular shape. The end 51 is provided with an inclined marginal flange 53 and has its upper edge recessed a short distance inwardly from the end, as shown at 54, and its lower edge recessed, as indicated at 55, inwardly from the end approximately twice the extent of the recess 54. The lower edge of the end 52 of the band is provided with two outwardly projecting lugs 56 and 57, the former being at the end of the band, and the latter being spaced inwardly a short distance therefrom. The upper edge of the band also has a lug 58 opposite to the lug 57. It is to be remembered that when referring to upper and lower edges of the band reference is made to the piston P that the band encircles, that edge which comes opposite the top of the piston being referred to as the upper edge, and the other edge, of course, being the lower edge.

The band 50 is provided with a second flange 59 (in the present instance crimped in the metal), said flange 59 being spaced a distance equal to about one-third the length of the band from the end 52 and inclined so that when the ends 51 and 52 are in overlapping relation (Figs. 9 and 10) the flanges 53 and 59 will diverge downwardly of the band. In order to draw the band tightly around the piston rings within the ring grooves of a piston, I provide what may be termed a wedge-plate 60 of arcuate contour, the side margins of the plate being oppositely inclined and terminating in inwardly bent flanges 61, 62 for the purpose of providing grooves 63, 64 to receive the flanges 53 and 59 respectively on the band 50. In order to give a wide range of adjustability to the ring compressor so that it will operate with equal facility on a wide range of piston sizes, the wedge-plate 60 is formed in two sections 65 and 66, the former being a good deal wider than the latter and having three rows of slots s, s' and s for receiving angle-shaped lugs or tongues t, t' and t. By adjusting the position of the tongues t, t', t in the slots s, s', s any desired spacing of the flanges 61, 62 may be obtained for compressing the band 50 to any desirable size, within of course the range of the device. It will be observed that the tongue t' is longer than the tongues t on either side of it, the object of which is to prevent the sections 65 and 66 from easily falling apart. By making the tongue t' of greater length a slight manipulation is necessary to separate the sections 65 and 66, thus avoiding accidental separation of these sections.

When the band 50 is to be applied to a piston and the rings thereof it is placed thereon with the ends 51 and 52 in overlapping relation so that the end 51 is confined between three lugs 56, 57 and 58. Then the wedge-plate (which has previously been adjusted to the right size) is disposed over the flanges 53 and 59 and slid downwardly thereon until the band has been drawn together so tightly that the piston rings are compressed so as to be entirely confined within their grooves. It often happens that before the piston rings have been completely compressed within their grooves the wedge-plate 60 will have been slid a considerable distance downwardly on the

flanges 53 and 59 so that the ends 51 and 52 of the band are held together only at the lower part of their width. Obviously, the pressure of the rings at the top of the piston would expand the upper edge of the band until it assumed a cone shape unless some means were employed to prevent this. In this form of the device the lugs 56, 57 and 58 prevent the band from assuming such cone shape, because they prevent the coiling movement at the ends of the band to effect such cone. The band is also provided with outwardly crimped portions 67 and 68 at its upper edge to insure that the band will not slip into the cylinder at any point when the piston is being pushed therein.

15 The provision of the confining lugs to prevent the band from assuming a cone shape in both forms of my piston ring compressor is of considerable importance. Obviously if the band is not so held that it will be unable to spread at its upper edge there is no assurance that the rings will be maintained compressed within the grooves. If the rings are not so held the device does not perform the function for which it is intended. For this reason there should be no coning out of the band, but it should remain perfectly cylindrical during the time that the piston is being pushed into the cylinder.

Having described my invention, I claim:

30 1. A piston ring compressor comprising a band having its ends adapted for overlapping cooperation to form a cylinder, adjustable securing means engaging said overlapping ends, and confining elements on both overlapping portions of the band for holding the ends in parallelism under the radial pressure imposed by the compressed piston rings.

2. A piston ring compressor comprising a band having its ends adapted for overlapping cooperation to form a cylinder, adjustable securing means engaging said overlapping ends, confining elements on both overlapping portions of the 5 band for holding the ends in parallelism under the radial pressure imposed by the compressed piston ring, and outwardly crimped portions in spaced relation on one lateral edge of the band.

3. A piston ring compressor comprising a band 10 having its ends adapted for overlapping cooperation to form a cylinder, securing means in proximity to said overlapping ends, and an applicator in combination with said band, said applicator having suitable devices for cooperating 15 with the securing means to contract the band and compress the piston rings, and circumferentially spaced cooperating elements on the band for holding the same cylindrical while being contracted.

4. A piston ring compressor comprising a band having its ends adapted for overlapping cooperation to form a cylinder, adjustable securing means engaging said overlapping ends, and confining elements disposed in circumferentially 20 spaced relation on one of the overlapping portions of the band for holding the other end in parallelism therewith under the radial pressure imposed by the compressed piston rings.

5. A piston ring compressor comprising a band 30 having its ends adapted for overlapping cooperation to form a cylinder, securing means for said overlapping ends, and circumferentially spaced cooperating elements on the band for holding the same cylindrical when unequal radial 35 pressure is applied to the margins of the band.

JOSEPH SUNNEN.
